UNITED STATES PATENT OFFICE.

ISAAC E. PALMER, OF MIDDLETOWN, CONNECTICUT.

DESIGN FOR A HAMMOCK.

No. 39,161.

Specification for Design.

Patented Feb. 25, 1908.

Application filed December 26, 1907. Serial No. 408,201. Term of patent 14 years.

To all whom it may concern:

Be it known that I, ISAAC E. PALMER, a citizen of the United States, residing at Middletown, in the county of Middlesex and State of Connecticut, have invented a new, original, and ornamental Design for Hammocks, of which the following is a specification, reference being had to the accompanying drawing, forming part thereof.

Figure 1 is a plan view of a hammock showing my new ornamental design.

I claim:

The ornamental design for a hammock, as shown.

In testimony whereof, I have signed my name to this specification, in the presence of two subscribing witnesses.

ISAAC E. PALMER.
